UNITED STATES PATENT OFFICE

LOUIS M. BLANTON, OF MIAMI, OKLAHOMA

LUGGAGE CARRIER FOR AUTOMOBILES

Application filed November 19, 1929. Serial No. 408,361.

This invention relates to luggage carriers for automobiles and has for its primary object to provide a carrier which, when not in use, may form a part of the automobile running board so that the usual contour of the running board will not be altered.

Still another object of the invention is to provide a luggage carrier designed to form a part of a motor vehicle running board which may be adjusted to different sizes in accordance with the amount of luggage to be transported.

A still further object of the invention is to provide a luggage carrier which may be opened out in such a manner as to provide a convenient camp table.

Other objects and advantages of the present invention will become apparent as the description of the same proceeds and the invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 shows a portion of a motor vehicle running board in plan showing the association of the present luggage carrier therewith.

Figure 2 is a sectional view taken upon the line 2—2 of Figure 1 showing the carrier closed.

Figure 3 is a sectional view similar to Figure 2 but showing the carrier in fully opened position.

Figure 4 is a view in plan of the luggage carrier opened out for use as a camp table.

Figure 5 is a sectional view taken substantially upon the line 5—5 of Figure 3.

Figure 6 is a sectional view taken upon the line 6—6 of Figure 4.

Referring more particularly to the drawings wherein like numerals of reference indi-

cate corresponding parts throughout the several views, the numeral 1 indicates the running board of a motor vehicle, the usual apron extending longitudinally of the back of the running board being indicated by the numeral 2.

The luggage carrier embodying the present invention is designed to form a permanent part of the running board 1 being positioned or sunk thereinto so that when it is in closed condition the top will be flush with or in the same plane as the top of the running board.

The carrier comprises a bottom 3 which consists of a fixed main portion 4 and a shiftable supplemental portion 5.

The portion 4 of the bottom is as shown of elongated rectangular contour and is relatively shallow, having the lower wall 6 and the integral upstanding back and side walls 7 and 8 respectively each of which is bordered by an inturned flange 9.

The supplemental bottom portion 5 consists of a lower part or plate 10 which rests upon the portion 6 and the upstanding end walls 11 which position against the inner faces of the adjacent end walls 8 to move thereagainst beneath the associate flanges 9. As shown the supplemental bottom portion 5 is adapted to slide into and out of the portion 4 and is slightly smaller than this portion so that when the carrier is closed up it will be housed in the main portion 4 of the bottom as shown in Figure 2.

Adjacent its outer edge the bottom section 6 of the bottom portion 4 has extending upwardly therethrough the bolts 12 one adjacent each side wall 8 and each of these bolts extends through a closed slot 13 formed through and transversely of the supplemental bottom portion 5, each bolt receiving upon its upper end a thumb nut 14 for holding the supplemental bottom portion 5 in a predetermined position relative to the portion 4.

The top of the carrier is indicated generally by the numeral 15 and as shown this part is made up of two sections like the bottom 3, one being the main top portion 16 and the other the supplemental top portion 17.

As clearly shown in Figure 3 the main top portion 16 has a right angularly extending

flange 18 formed longitudinally of its outer edge which flange is of a width slightly greater than the over-all depth of the carrier and is hingedly attached at its free edge as indicated at 19 to the outer edge of the supplemental bottom portion 5.

The supplemental top portion 17 is designed to slide over the inner face of the portion 16 and is adjustably held in contact therewith by means of the bolts 20 which extend through and are secured to the main top portion 16 adjacent its inner edge which bolts extend through the slots 21 formed through and transversely of the top portion 17 in the manner illustrated in Figure 4, wing nuts 22 being mounted upon the bolts for securing the main and supplemental top portions together.

The free edge of the supplemental top portion 17 is also provided with an inwardly projecting longitudinally extending flange 23 which, when the top is closed down over the bottom, extends into the rear part of the bottom portion 4 to rest upon the bottom 6 thereof as shown in Figure 2.

Pivots secured as at 24 to the inner face of the back 7 of the main bottom portion, adjacent each side thereof, is a telescoping brace rod 25 the outer end of which is offset 30 to form a hook 26 with which may be employed a pivoted latch 27 for engaging across the open part thereof after the hook has been engaged through a keeper such as that indicated at 28 mounted upon the inner face of the flange 23 of the supplemental top portion 17. The sections of the telescoping brace rod 25 are maintained in adjusted position by means of set screws 29, the manner in which this function is performed being readily apparent.

From the description thus far given it will be seen that when the luggage carrier is not in use it forms a permanent part of the vehicle running board, its top surface being flush with the surface of the running board and its width being substantially equal to that of the running board so that slight change in the appearance of the board is apparent.

If the carrier is to be used for the transportation of relatively small articles the top may be swung up upon the hinges 19 and secured in upright position by means of the brace rod 25 which, when the carrier is not in use, is shortened up to lie therein as shown in Figure 2. The supplemental bottom 5 and top 17 each remains in its associate part of the carrier so that the height and width of the carrier is equal to its width when in folded condition. If the carrier is to be enlarged then the thumb nuts 14 and 22 may be loosened so that the supplemental parts 5 and 17 may be shifted upon their respective supports until the carrier is opened to its

full size. It will then appear as shown in Figure 3.

For use as a camp table the carrier may be opened to its full size and the top 15 swung out until it is in a plane substantially parallel with the plane in which the bottom 3 lies. Detachable leg elements 30 may then be mounted upon the flange 23 at the free edge of the supplemental top portion 17 to support this outer part of the carrier. The top surface of the same may then be used for supporting table articles and food.

While any means may be employed for mounting the legs 30 upon the top of the carrier I prefer to form the legs of angle iron material and to extend one flange of the same and bend it back upon itself as indicated at 31 to form a hook for engagement over the flange 23; the adjacent end edge of the other flange of the leg extending beneath the top portion 17 as indicated at 32 to provide a firm surface upon which the top may rest.

From the foregoing description it will be readily seen that a luggage carrier constructed in accordance with the present invention may form an inconspicuous accessory for an automobile and may be easily and quickly arranged in working position and in such position will provide a strong and serviceable bundle carrier.

Having thus described my invention, what I claim is:—

1. A motor vehicle luggage carrier comprising a tray-like body designed to form a part of a motor vehicle running board and having end and back flanges, a tray-like top portion, hinge connecting means between adjacent edges of the top and bottom portions whereby the top may be swung to a vertical position at the outer edge of the bottom portion or to a horizontal position in substantially the same plane as the bottom portion and within the flanges thereof, means connecting the two portions whereby same may be maintained in adjusted position, and means whereby each of said portions may be made of increased width.

2. A running board luggage carrier for motor vehicles comprising a tray-like body constituting the bottom of the carrier and comprising a bottom, an inner wall and side walls, the body being set into the running board to dispose the top flush with the top of the running board, a second body constituting the top of the carrier and having inner and outer longitudinal walls, a hinge connection between said outer longitudinal wall and the outer edge of the first body whereby the second body may be disposed over and fitted into the first body or swung relative thereto, the said outer longitudinal wall forming an outer edge wall for the tray body when the carrier is closed, and an elongated longitudinally adjustable connecting means

between the bodies for maintaining the same in predetermined relative positions.

3. A luggage carrier for motor vehicles comprising a tray-like body constituting the bottom of the carrier and comprising a bottom, an inner wall and side walls, the body being set into the running board to dispose the top flush with the top of the running board, a second body constituting the top of the carrier, a hinge connection between said second body and the outer side of the first body whereby the second body may be disposed over and fitted into the first body or swung relative thereto, and adjustable connecting means between the bodies for maintaining the same in predetermined relative positions, each of said bodies being formed in two adjustably connected sections whereby the width of each body may be increased.
- 10 4. A motor vehicle luggage carrier comprising an elongated rectangular receptacle of substantially the same width as a running board and designed to be sunk thereinto to dispose its top flush with the top of the running board, said receptacle comprising a top and a bottom, said bottom consisting of a main and an auxiliary portion, the main portion having side walls and an inner wall, the auxiliary portion having side walls slidably associated with the main portion side walls, means for securing said main and auxiliary portions in adjusted relation, said top comprising a main and an auxiliary portion, said main portion having an outer longitudinally extending wall, and said auxiliary top portion having a longitudinally extending wall, a sliding connection between said main and auxiliary top portions whereby the width of the top may be increased, a hinge connection between the longitudinally extending wall of the main top portion and the auxiliary bottom portion, and longitudinally adjustable brace members connecting the top and bottom of the receptacle for maintaining the same in adjusted position.
- 15 5. A luggage carrier of the character described comprising a receptacle of elongated rectangular contour formed of a top and a bottom section, said top and bottom sections each being formed in two parts whereby the width of each section may be increased, a hinge connection between said top and bottom sections at one longitudinal side thereof, and a longitudinally adjustable brace rod adapted to connect the inner side of the bottom section with the top section at its outer longitudinal edge for maintaining the sections in predetermined relative positions.
- 20 6. A luggage carrier of the character described comprising a receptacle of elongated rectangular contour formed of a top and a bottom section, said top and bottom sections each being formed in two parts whereby the width of each section may be increased, a hinge connection between said top and bot-

tom sections at one longitudinal side thereof, and adjustable brace rod adapted to connect the inner side of the bottom section with the top section at its outer longitudinal edge for maintaining the sections in predetermined relative positions, said bottom section being designed to form a part of a motor vehicle running board and said top section being adapted to be swung to a position substantially in the same plane with the bottom section, and detachable leg members adapted to be connected with the top section to maintain the sections in position for use as a table.

25 7. A luggage carrier for motor vehicles, comprising a tray-like body constituting the bottom of the carrier and comprising a bottom formed in two sections, one lying and slideable upon the other, an inner wall and side walls carried by the under one of the two sections, the bottom being set into the running board to dispose the top flush with the top of the running board, a second body constituting the top of the carrier and comprising two sections normally disposed in juxtaposition, one of the two sections of both the top and bottom of the carrier having transverse slots therein, pins carried by the other sections of the top and bottom of the carrier and engaging in the slots of the adjacent sections, means carried by said pins for securing the sections in adjusted position relative to one another, a hinge connection between said second body and the outer side of the first body whereby the second body may be disposed over and fitted into the first body or swung relative thereto, and adjustable connecting means between the bodies for maintaining the same in pre-determined relative positions.

In testimony whereof I hereunto affix my signature.

LOUIS M. BLANTON.
